UNITED STATES PATENT OFFICE.

DICK LEWALLEN, OF MANHATTAN, KANSAS.

FEEDING DEVICE FOR THRESHING-MACHINES.

1,122,958.

Specification of Letters Patent. Patented Dec. 29, 1914.

Application filed June 20, 1913. Serial No. 774,871.

To all whom it may concern:

Be it known that I, DICK LEWALLEN, a citizen of the United States, residing at Manhattan, in the county of Riley and State of Kansas, have invented new and useful Improvements in Feeding Devices for Threshing-Machines, of which the following is a specification.

This invention relates to feeding devices for threshing machines, and it has particular reference to that type of feeding devices which are used for feeding loose or unbound grain.

One object of the invention is to produce a simple and improved machine which may be situated between two stacks of grain for the purpose of feeding simultaneously from the two stacks.

A further object of the invention is to produce a simple and improved construction whereby the main frame of the machine, which is normally supported for transportation on wheel carrying trucks, may be lowered or adjusted so as to practically rest on the ground whereby it will be firmly supported when the machine is in operation.

A further object of the invention is to combine with the main or supporting frame a vertically movable track frame and simple and improved means whereby said track frame may be elevated to a starting position and lowered gradually by a step by step movement as the operation progresses, means being also provided for gaging the extent of the step by step movement.

A further object of the invention consists in the provision of a reciprocating carriage traveling on the track frame and having stack engaging devices for conveying the grain from the stack to another carrier supported by the main frame, and whereby said grain is in turn conveyed over the elevating carrier to the threshing machine.

Still further objects of the invention are to simplify and improve the various structural details of the machine.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood

that no limitation is necessarily made to the precise structural details therein exhibited, but that changes, alterations and modifications within the scope of the claims may be resorted to when desired.

In the drawings, Figure 1 is a side elevation of a machine constructed in accordance with the invention, showing the main frame lowered in position for operation. Fig. 2 is a top plan view of the same. Fig. 3 is a transverse sectional detail view taken through the track frame on the line 3—3 in Fig. 2, and showing the reciprocating carriage in elevation, said figure being drawn to a larger scale. Fig. 4 is a sectional detail view, also enlarged, taken on the line 4—4 in Fig. 2. Fig. 5 is a top plan view of one end of the main frame. Fig. 6 is an end view in elevation of the parts shown in Fig. 5. Fig. 7 is a sectional detail view taken on the line 7—7 in Fig. 5. Fig. 8 is a sectional detail view taken on the line 8—8 in Fig. 6 to show the escapement device. Fig. 9 is a detail plan view of a worm gear and pinion used in connection with the device. Fig. 10 is a detail view in elevation of the shifting rod and related parts. Fig. 11 is a horizontal sectional detail view of one of the corner uprights of the main frame, showing a portion of the track frame connected therewith. Fig. 12 is a sectional detail view taken on the line 12—12 in Fig. 4. Fig. 13 is a sectional detail view taken on the line 13—13 in Fig. 1. Fig. 14 is a sectional detail view taken on the line 14—14 in Fig. 1.

Corresponding parts in the several figures are denoted by like characters of reference.

The main frame of the improved machine includes in its construction four corner posts or uprights 15 which are suitably connected together near their upper and lower ends by side bars 16 and end bars 16' to form a substantially rectangular frame of suitable height to be used in connection with tall stacks of grain and of a length which will enable large stacks to be operated upon, the length being in excess of the height, as will be understood by reference to Fig. 1, where parts have been broken out intermediate the ends of the frame structure. The frame structure is also relatively narrow so that it may be readily driven in between two stacks and located in position for operation.

The main frame is supported by front and rear trucks 17, 18, said trucks being supported on wheels 19, 20. The wheels of the

front truck are designed to swing beneath the truck for convenience in turning; the wheels of the rear truck may be connected up to a steering rod 21 having a hand wheel 22 for convenience in steering the machine while being transported. The front and rear trucks are each provided with vertical guides 23 for the main frame, each of said guides supporting a shaft 24 carrying pinions 25 in mesh with racks 26 on the main frame. Each of the shafts 24 also carries a gear 27 meshing with a worm 28 on a shaft 29 having a crank 30 whereby it may be rotated. It will be observed that by operating the worm carrying shafts 29 the shafts 24 at the two ends of the frame may be rotated independently, thereby enabling the main frame to be raised or lowered, as may be desired. The adjustment of the two ends being independent, it is obvious that it may be accommodated to uneven ground so that the main frame may be set in a level position when the front and rear trucks are at different elevations. The main purpose in providing this adjustment is to enable the main frame to be raised or lowered for transportation and lowered so as to rest on the ground when the feeding device is in operation. In Fig. 1 of the drawings the main frame has been shown supported on level ground, the corner posts or uprights 15 being slightly extended downwardly below the lower side rails 16 so as to form ground engaging feet. It is obvious that if the ground is not quite level, the main frame may be propped, wedged or supported in any suitable manner to maintain it in an upright and level position while in operation.

40. The uprights or corner posts of the main frame preferably consist of I-beams, as seen clearly in Fig. 11 of the drawings. Supported for vertical movement on said corner posts is a track frame 31 which may be provided adjacent to the corners thereof with clips 32 engaging the uprights so as to permit the track frame to slide vertically. Supported for rotation on the main frame at one end thereof is a shaft 33 carrying a drum 34 upon which four flexible elements, such as ropes or cables 35 are independently wound, said cables being guided over suitable guiding means, such as pulleys 36 to the four corners of the track frame with which they are connected, thereby serving to support the said track frame in a substantially level position and enabling it to move freely upwardly and downwardly, as the cables are being wound upon or unwound from the drum.

45. The drum carrying shaft 33 is provided at one end with a spur wheel 34' meshing with a pinion 35' which is loose on a shaft 36, said pinion being adapted to be driven by means including a clutch 37 for the purpose of transmitting motion to the drum. The shaft 36 is connected by bevel gearing 38 with a counter shaft 39 carrying a gear wheel 40 meshing with a worm or spiral 41 on a disk 42 carried by a vertical tubular shaft 43 supported for rotation on a shaft 44. The shaft 44 carries at its upper end one member 45 of a centrifugal friction clutch of conventional construction, the other member of which, 46, is carried by the tubular shaft 43. The shaft 44 carries at its lower end a bevel gear 47 meshing with a bevel gear 48 on the main driven shaft 49 which carries a belt wheel or pulley 50 adapted to receive motion from the threshing machine in connection with which the feeder is used or from some other suitable source of power. It will be seen that by the means described, motion may be transmitted from the main driven shaft to the drum 34 for the purpose of rotating the latter to wind the cables 35 thereon in order to move the track frame 31 in an upward direction on the main frame structure, the transmission means including the clutch 37 which may be thrown to an inactive position automatically by means to be presently described.

50. The clutch 37 may be actuated by means of a shipping lever 51 which is in the nature of a bell crank, one arm of which is provided with an extension 52 lying in the path of the track frame 31 so as to be engaged by the latter when it approaches the top of the main supporting frame. When the track frame approaches the limit of its upward movement, the shipping lever will be actuated to operate the clutch, thereby releasing or disengaging the drum from the hoisting mechanism without interfering with the rotation of the shaft 36.

55. The spur wheel 34' on the drum carrying shaft meshes with a pinion 53 which is situated diametrically opposite to the pinion 35', said pinion being mounted on a shaft 54 which carries a plurality of escapement wheels or disks 55, each provided at its perimeter with ratchet teeth 56, but each of said wheels or disks having a different number of ratchet teeth. A counter shaft 57 is adjustably supported in bearings 58 in a position substantially parallel to the shaft 54, said counter shaft 57 being longitudinally slidably in its bearings where, however, it may be secured in adjusted position by means such as set screws 59. The shaft 57 carries an escapement lever 60 which by proper adjustment of the shaft may be placed in engagement with any one of the disks 55, said escapement lever being provided with teeth 61, 62, one or the other of which will always be positioned in the path of the teeth 56 of the wheel 55 temporarily engaged by the escapement lever to co-operate therewith. It will be seen that by rocking the escapement lever, the shaft carrying 130

the escapement wheels may be permitted to rotate under the influence of the weight of the track frame which is supported by the flexible elements 35 wound on the drum 34 which is geared up to the shaft 54 carrying the escapement wheels. It will also be obvious that the extent of the rotation will be determined by the number of teeth on the individual escapement disks. Thus, by shifting the position of the shaft 57 to place the escapement lever in engagement with one or the other of the escapement wheels, the extent of the gravitational downward movement of the track frame at each step may be regulated. It is obvious that the number of escapement wheels, as well as the number of teeth on each wheel, may be varied. For the purpose of checking the rotation to avoid a too sudden downward movement of the track frame any convenient friction brake mechanism may be employed. In the drawing a bearing member 63 has been shown having screws 64 which frictionally engage one of the escapement wheels, but the construction and arrangement of the brake mechanism may be varied, and any convenient well known mechanism may be employed for this purpose.

For the purpose of actuating the escapement lever 60, mechanism is provided including an arm 65 depending from one end of said lever and lying in the path of a contact plate 66 carried by an arm 67 extending from a shifting rod 68. Said rod is supported by means of cranks 69 on the main frame structure in such a manner that movement of the said rod laterally in any direction will serve at the same time to lift or elevate the rod bodily, thus causing the contact plate 66 to engage the arm 65 of the escapement lever, thereby tripping the latter, thus throwing the tooth 61 out of engagement with the tooth 56 of the escapement disk engaged thereby and placing the tooth 62 in the path of the next succeeding tooth 56, permitting the escapement disk to make a partial rotation; a retracting spring 70 for the escapement lever is provided for the purpose of restoring the latter to its initial position after being tripped by the contact plate, thus releasing the tooth 56 of the escapement wheel that was intercepted by the tooth 62 and permitting it to pass into engagement with the tooth 61 of the escapement lever, thereby completing the partial rotation of the escapement wheel which constitutes one step of the movement.

Supported for rotation in suitable bearings adjacent to one corner of the main frame structure is a vertical shaft 71, said shaft being of non-circular cross section, and said shaft being provided at its upper end with a bevel gear 72 meshing with a bevel gear 73 on the shaft 36 through which it derives motion from the main, driven

shaft 49 which carries the belt wheel 50. The vertically movable track frame 31 carries a bracket or bearing member 74 equipped with sleeves 75 surrounding and slidably engaging the non-circular shaft 71. 70 A bevel gear 76 which is interposed between the bearing sleeves 75 engages the non-circular shaft 71 and is rotatable therewith while free to slide thereon, as will be readily understood. The bracket 74 also supports 75 one of the bearings 77 of a shaft 78 that extends longitudinally of the track frame adjacent to one side thereof, the other end of the shaft 78 being supported in a bearing 79 adjacent to the opposite end of the frame. 80 The shaft 78 carries a bevel gear 80 meshing with the bevel gear 76 on the shaft 71 from which motion will thus be transmitted to the shaft 78 in any position occupied by the track frame. The shaft 78, as will be 85 best seen in Fig. 3, is of non-circular cross section throughout the greater portion of its length.

A reciprocating carriage C is mounted to move longitudinally of the track frame 31, 90 said carriage being provided with supporting wheels 81. The carriage supports about midway of its length a revoluble drum 82 on which is partly wound a flexible element, such as a cable 83, the ends of 95 which are secured upon the ends of the track frame, as indicated at 84. It will be seen that by rotating the drum 82 one end portion of the cable 83 will be wound upon, while the other end portion will be 100 unwound from said drum, and the carriage will thus be caused to travel along the track frame, the direction of travel being governed by the direction in which the drum is rotated. For the purpose of rotating the 105 drum and of changing the direction of rotation, the drum is provided with a bevel gear 85 meshing with opposed bevel gears 86, 86' which are loosely mounted for rotation on a shaft 87 supported in bearing 110 brackets 88 on the carriage, see Fig. 4. The beveled gears 86, 86' are provided with clutch members 89, 89' adapted to be engaged by a clutch sleeve 90 which is slidable on and rotatable with the shaft 87, said 115 clutch sleeve being operable by a shifting lever 91 which is fulcrumed on the carriage. It will be seen that by placing the clutch sleeve in engagement with one or the other of the clutch members 89, 89' the direction 120 of rotation of the drum 82 may be regulated, said drum deriving motion from the shaft 87, as will be readily understood. It will be further seen that by placing the clutch sleeve 90 in intermediate non-engaging position with respect to the clutch members, the rotation of the drum may be discontinued, while the shaft 87 continues to 125 revolve. The shaft 87 is constantly driven from the non-circular shaft 78 when the ma- 130

chine is in operation by means of a pinion 92 slideable upon and rotatable with the shaft 78 and transmitting motion through a spur wheel 93 to the shaft 87. The carriage is provided at opposite sides thereof with brackets 94 on which conveyer frames 95 are pivotally supported, said conveyer frames being equipped with endless conveyers including belts or aprons 96 having transverse slats 97 provided with teeth 98. The endless conveyers are guided over shafts 99 on which the conveyer frames are pivotally supported; one of said shafts, 99, is driven by means of a chain 100 from a counter shaft 101 having a spur wheel 102 meshing with the pinion 92 on the non-circular shaft 78. The conveyer shaft 99 at the opposite side of the carriage is driven by means of a chain 103 from a counter shaft 104 which derives motion by means of a chain 105 from a sprocket wheel 106 on the shaft 87, said chain 105 extending transversely across the carriage, as best seen in Fig. 2.

Connected with the free ends of the conveyer frame 95 are the bifurcated ends 107 of cables 108, the opposite ends of which are connected with and wound upon drums 109 whereby the free ends of the conveyer frames may be raised and lowered to various adjustments.

Supported on the track frame adjacent to the ends thereof are levers 110, 110, the oppositely extending arms of which are connected by members, such as rods or wires 111, 112. One of the levers 110 has a laterally extending arm 113 carrying at the end thereof a U-shaped clip 114 embracing the shifting rod 68 so as to be capable of moving vertically along the latter without being interfered with by the supporting cranks 69. The connecting member 112 carries adjustable stop members 115 which are disposed in the path of a tappet member 116 associated with the carriage C. Stop members 117 are suitably associated with the track frame with respect to which said stop members are also adjustable, said stop members being disposed in the path of the shipping lever 91 which actuates the clutch member 90, the position of which will thus be reversed whenever the carriage approaches the limit of its movement in either direction.

Supported on the bottom portion of the main frame structure and operating lengthwise thereof is an endless conveyer 118, said conveyer being disposed in an approximately horizontal plane. An elevating conveyer 119 is supported in a frame 120 at one end of the main frame structure, said elevating conveyer being arranged to receive material from the conveyer 118 for the purpose of elevating the same and delivering it to the threshing machine. The conveyers

118, 119 are driven by intermediate gearing 121 from the lower end of the shaft 71, motion being also transmitted from such intermediate gearing by means of a belt or band 122 to a feed cylinder 123 having radially extending teeth 124 and which serves to assist in transferring the loose grain from the conveyer 118 to the conveyer 119. Extending longitudinally of the conveyer casing 120 are resilient guard bars 125 which in practice serve to prevent the loose grain from being blown off from the carrier or conveyer 119.

In the operation of this device, the machine is driven between the stacks which are to be fed to the threshing machine, and the main supporting frame is lowered to rest on the ground or practically so. In order to move the track frame to the upper end of the main supporting frame motion is transmitted from the source of power to the band wheel 50 and thence through the intermediate mechanism including the worm or spiral 41 and the gear wheel 40 on the shaft 39 to the shaft 36 which, the clutch 37 being set in active position, will transmit motion to the drum 34 on which the cables 35 will be wound, thus lifting or elevating the track frame and the carriage until the track frame strikes the depending arm 52 of the shipping lever 51, thereby throwing the clutch out of gear. While this operation is in progress, the teeth 56 of the escapement wheel 55 engaging the escapement lever will pass idly over the tooth 61 of said lever. When the clutch 37 is thrown by the shipping lever 51, the escapement device will serve to support the track frame in its elevated position, it being understood that the clutch 37 remains out of commission until the shipping lever is reset manually. When the clutch is disengaged, the spur wheel 35' will no longer resist the reverse rotation of the drum caused by the weight of the track frame and the parts supported thereon, the dropping of the track frame being resisted only by the escapement device. It will, furthermore, be understood that during the period that the track frame is being elevated, the clutch member 90 should occupy a neutral position between the clutch members 89, 89' so that while rotary motion is transmitted from the shaft 71 through the transmission means including the shaft 78 to the shaft 87, the carriage will remain stationary on the track frame because the drum 82 will not be actuated. To start the carriage after the desired elevation has been attained, it is only necessary to move the shipping lever 91 to one side or another, thereby placing the clutch member 90 in engagement with either one of the clutch members 89, 89', but before this is done, the conveyer frames 95 at the two sides of the carriage are adjusted so as to cause the endless conveyers includ-

ing the members 26 and the slats 27 to rest on top of the two stacks over which they extend, the conveyers being operated in such fashion that the lower leads of the conveyers will pull material from the top of the stack and deliver it in an inward direction toward the sides of the main frame structure where it will drop on the conveyer 118 or adjacent to the sides thereof, the piles adjacent to the sides of the conveyer soon attaining such height that material will topple or gravitate therefrom on to the conveyer, whereby said material is transferred to the elevating carrier 119. While the conveyers supported in the frames 95 are operated in this manner, being set at any desired inclination, the carriage will reciprocate upon the track, being actuated by the rope 83 wound on the drum 82, which latter will be alternately rotated in opposite directions by the means provided for the purpose and including the clutch members 89, 89' and the clutch sleeve 90, the position of the latter being changed by the shifting lever 91 whenever the latter is engaged by one of the stop members 117. Whenever the carriage approaches the limit of its prescribed movement, the member 116 will engage one of the stops 115, thereby imparting a rocking movement to the levers 110, the arm 113 of one of which carries the clip 114 engaging the shifting rod 68 which will thus be moved in an upward direction until the stop member or plate 66 engages the arm 65 depending from the escapement lever 60, tripping the latter with the result of causing the track frame to be gravitationally lowered to the extent of one step of predetermined length.

Having thus described the invention, what is claimed as new, is:

1. In a device of the class described, a supporting frame, a track frame vertically movable thereon, a reciprocatory carriage on said track frame, endless carriers associated with and extending laterally from the carriage, means for elevating the track frame by a continuous uninterrupted movement, means for automatically stopping the track frame at the upward limit of its movement, and means including an escapement device for causing the frame to descend gravitationally by an intermittent step by step movement.

2. In a device of the class described, a supporting frame, a track frame vertically movable thereon, means for elevating the track frame to a starting position, means for interrupting the upward movement of the track frame when the starting position is reached, means including an escapement device for causing the track frame to descend

gravitationally by an intermittent step by step movement, a carriage mounted for reciprocation on the track frame, and means actuated by the carriage for tripping the escapement device at the limits of the movement of the carriage.

3. In a device of the class described, a main frame structure, a track frame vertically movable thereon, means including an escapement device for lowering the track frame gravitationally by an intermittent step by step movement, a carriage mounted for reciprocation on the track frame, means actuated by the carriage for tripping the escapement device at the limits of the movement of the carriage in either direction, operating means for the carriage, reversing means for said operating means including a clutch and a shifting lever, and means for actuating the shifting lever on the completion of the movement of the carriage in either direction.

4. In a device of the class described, a main supporting frame, a track frame vertically movable thereon, a carriage mounted for reciprocation on the track frame, elevating means for the track frame, means including an escapement device for lowering the track frame, operating means for the carriage, reversing means for said operating means, an endless carrier hingedly connected with and extending laterally from the carriage, operating means for said carrier, an endless carrier extending longitudinally of the main frame structure in the lower portion thereof, an elevating carrier adjacent to one end thereof, and operating means for said last mentioned endless and elevating carriers.

5. In a device of the class described, a main frame structure, a track frame vertically movable thereon, a carriage mounted for reciprocation on the track frame, endless carrying means hingedly associated with the carriage, an endless carrier disposed longitudinally in the lower part of the main frame structure, an elevating carrier adjacent to one end thereof, and operating means for the moving parts of the device including a driven vertical shaft adjacent to one corner of the main frame structure, said shaft being of non-circular cross section, and means for transmitting motion from said non-circular shaft to the moving parts associated with the track frame in various positions of the latter.

In testimony whereof I affix my signature in presence of two witnesses.

DICK LEWALLEN.
